EDWARD PREVEAR, OF LEOMINSTER, MASSACHUSETTS.

Letters Patent No. 82,984, dated October 13, 1868.

IMPROVEMENT IN MERIDIAN-TIME INDICATOR.

The Schedule referred to in these Letters Patent and making part of the same.

To all whom it may concern:

Be it known that I, EDWARD PREVEAR, of Leominster, in the county of Worcester, and State of Massachusetts, have invented and made a certain new and useful improved Meridian-Time Indicator; and I do hereby declare the following to be a full, clear, and exact description of the same, reference being had to the annexed drawing, making part of this specification, wherein—

Figure 1 is a vertical section of my apparatus, and Figure 2 is a plan of the same.

Similar marks of reference denote the same parts.

This invention consists in an instrument for indicating meridian time with great accuracy. It is portable, and not liable to injury either from exposure or in handling, and the apparatus is adapted to use at any season of the year, regardless of the sun's declination.

This invention consists in a fixed bed-plate, formed with bearings to receive a swinging meridian-arm and lens. The bed-plate is to be attached to a firm post or other support, so that the bearings for the arm stand east and west, in order that the arm may be swung in the plane of the meridian, to accommodate the position of the sun or of any star when crossing the meridian, and thereby determine accurately the time by moving said arm, so that a shadow or reflection is cast on an index on the meridian-arm. The meridian-arm, when not in use, may be detached from the plate and properly housed.

In the drawing, *a* represents the top of a post or other firm support, to which the bed *b* is attached by suitable screws, *c*, or other means, and adjusting-screws

may be employed, as at *d*; and upon the plate or bed *b* are bearings *e e*, for the journals *f* of the meridian-arm *g*.

The bearings *e e* are made forked, so that the journals *f* can be removed easily or set into their places, and pins, *h*, may be introduced over the journals, to keep them in place, but allow the arm *g* to be raised or lowered at its outer end, so as to come on line with the sun or other body crossing the plane of the meridian.

I employ a lens at *i*, through which the rays of light pass, and the focus thereof is the index *k*, that is divided into minutes to the sides of the nonius, so that the observation can be made a few minutes before or after the body crosses the meridian.

It will be understood that the arm *g*, swinging in the plane of the meridian, will indicate correctly meridian time, and will be a great convenience for determining accurately the time of day under circumstances where the true time cannot be easily obtained by other observations.

What I claim, and desire to secure by Letters Patent, is—

The meridian-arm *g*, fitted to swing, in combination with the lens *i* and index *k*, substantially as specified.

In witness whereof, I have hereunto set my signature, this 2d day of October, 1867.

EDWARD PREVEAR.
